REGULATOR FOR VEHICLE WINDOWS

Stanley W. Nicholson, Toledo, Ohio, assignor, by
mesne assignments, to Detroit Harvester Com-
pany, Detroit, Mich., a corporation of Michigan

Application June 29, 1937, Serial No. 150,995

2 Claims. (Cl. 268—126)

This invention relates to vehicle window regulators such as used for raising and lowering the windows of automobiles but more particularly to a regulator of the type shown and described in the application of Stanley W. Nicholson, Serial No. 132,738, entitled "Vehicle window regulator". An object is to produce a new and improved regulator of the above character in which the mechanism can be conveniently operated from a remote point thereby enabling the handle location to be arranged on the inside of the door at any desired place.

Another object is to produce a remote control drive for a regulator of the so-called jack knife type employing links or translatory members as an operative connection between the remote control drive of the regulator unit.

Other objects and advantages of the invention will hereinafter appear and, for purposes of illustration, an embodiment of the invention is shown on the accompanying drawings in which

Figure 1 is a side elevation of the regulator mechanism with its remote control drive, showing the regulator connected to the lower edge portion of the window;

Fig. 2 is a fragmentary elevation of the mechanism shown in Fig. 1 showing the position of the parts at the time when the link is about to be freed from the crank arm;

Fig. 3 is a vertical sectional elevation on the line 3—3 of Fig. 1; and

Figs. 4 to 8 are partly elevational and partly diagrammatical views showing the position of the various parts from the fully raised position of the window glass to its completely lowered position, particularly illustrating the operation of the remote control device and its connecting links.

The illustrated embodiment of the invention comprises a regulator mechanism having a mounting plate 10 which is suitably secured to cross bars or supports 11 and 12 carried on the inside of a vehicle door. Pivotally mounted on the plate 10 on a stud 13 is a triangularly shaped crank arm 14 to one end of which is pivoted by a stud or rivet 15 a link 16, the outer or free end of which carries a stud or roller 17 riding in a horizontal guide 18 in a retainer 19 which is suitably fixed to and depends from a channel 20. The channel 20 is secured to the lower edge of a window glass 21. The crank arm 14 is formed with oppositely extending ears or rests 22 to receive the link 16 when the latter is in abutment with the crank arm as shown in Fig. 1.

Forming a part of the mounting plate 10 is an extension 23 at its upper end portion and

integral with this portion is an outwardly extending flange 24 which is arcuately shaped, as indicated on Fig. 1. Intermediate the ends of the link 16 is mounted an outwardly projecting pin 25 which is adapted to ride beneath the flange 24 thereby to hold the link 16 and arm 14 in constant angular relation during a portion of the swinging movement of the arm. It will be apparent that during a portion of the swinging movement of the crank arm 14, the arm and link 16 operate together as a bell crank lever but after the pin 25 is freed from the flange 23, the link 16 functions as a link for raising or lowering the window glass 21. It is not believed that further detailed description of the construction and arrangement of the regulator need be given, reference being made to my co-pending application hereinbefore referred to for more complete description.

In some instances, it is desirable that the actuating or driving means for the regulator be disposed at a point remote from the regulator. This is particularly true in the case of automobile doors which are extremely wide and where it is necessary or desirable that the actuating handle be located a sufficient distance in front of the seat to enable it to be conveniently operated. Ordinarily, the regulator can not be moved to that portion because of interference with other parts or because for best operation the force should be applied to the window substantially centrally thereof. In this instance, the crank arm 14 of the regulator is operated by a remote control mechanism R which may be spaced a substantial distance from the regulator. As shown, the remote control R comprises a mounting plate 26 which is secured by rivets 27 to the supporting plates or bars 11 and 12 respectively. Secured to the plate 26 is a spring clutch device 28 having a squared shaft 29 on which an operating handle 30 is fitted. Also forming a part of the clutch mechanism is a pinion 31, the arrangement being such that upon turning the handle 30, the pin 31 may be rotated in one direction or the other and a coil spring (not shown) cooperates with the clutch housing to prevent retrograde movement of the pinion 31. Clutches or brakes of this character are well-known to those skilled in this art and further detailed description is not considered necessary.

Mounted for turning movements on a stud 33 of the mounting plate 26 is a gear 34 with which the pinion 31 meshes. As shown, the teeth of the gear do not extend entirely around the outer surface thereof but sufficient teeth are provided

to secure the desired movement of the crank arm 14 as hereinafter appears.

The gear 34 is positively connected to the crank arm 14 by links or straps 35 and 36. The links 35 and 36 are arranged in parallel relation and are connected respectively to opposite sides of the gear 34 and arm 14. It will be apparent that the link 35 is pivoted at its ends to the gear 34 and arm 14 on one side thereof and the link 36 is pivotally connected to the gear and arm on the opposite side. The opposite ends of the link 36 are pivotally connected to the respective parts at points equally spaced from the axes of the gear 34 and arm 14. Similarly, the pivotal connections of the link 35 are equi-distantly spaced from the axes of the gear and arm. This arrangement enables the arm 14 to be swung in one direction or the other by turning movements of the gear 34, one of the links exerting a pulling force against the arm 14 and the other exerting a pushing force as will readily be apparent.

An inspection of Figs. 4 to 8 will show the manner in which the parts operate. In Fig. 4, the window is shown in its fully raised or closed position, the link 16 and arm 14 being held in abutment with each other so that these parts function as a bell crank lever. By turning the handle 30 in counterclockwise direction (Fig. 4) clockwise rotation is imparted to the gear 34, whereupon a pushing force is imparted to the link 35 and a pulling force is imparted to the link 36, thereby causing the link 16 and arm 14 to be swung in a clockwise direction. As will be apparent, these parts are held in abutment relation by engagement of the pin 25 with the flange 24. Continued movement of the handle 30 in the same direction causes the pin 25 to pass from the flange 24 as shown on Fig. 6 and in this instance, the link 36 is uppermost, the gear 34 imparting a pushing force to the link 36 and a pulling force being initiated against the link 35. In this position, the link 16 is freed from the crank arm 14 and a downward pushing force is exerted by the link against the window to continue its lowering movement, although the link is juxtaposed to the arm 14.

Figure 7 shows the parts in the position assumed when further lowering movement is effected in which the link 16 is moved farther away from the arm 14. Finally Fig. 8 shows the position of the parts when the window is in its fully lowered position, the links having been correspondingly moved as will be readily understood.

In the position of the parts shown in Figs. 5 and 7, during the raising of the window, the remote control R is subjected to its greatest load. For that reason, the links 35 and 36 are so connected that they exert their maximum force at

the most favorable angle. At that time, as in Fig. 5, the link 35 is in such position as to exert its maximum pulling force and shortly beyond that position, the link 36 functions to exert a most effective pushing force. Obviously, from the position of the parts in Fig. 7, an exceedingly strong pushing and pulling force is exerted by the link during the raising of the window. There are no dead centers in the arrangement shown.

It will be manifest that the remote control can be disposed in one of a number of different positions and, if necessary, in angular relation to the regulator thereby to fit the various requirements of service. The link connection between the remote control R and the regulator provides a positive and reliable connection which can be inexpensively manufactured but which is sturdy, reliable and efficient. Although the above described remote control is particularly advantageous with a regulator of the type shown in which the crank arm moves through an arc of about 240°, it can be used satisfactorily with other regulators.

Although I have shown and described the best form known to me at the present time, it is to be understood that changes in details of construction, arrangement and operation may be effected without departing from the spirit of the invention especially as defined in the appended claims.

What I claim is:

1. A vehicle window regulator comprising a crank arm, a link pivoted to one end of said arm, means for connecting the opposite end of said arm to a window, abutment means on said arm against which said link bears for a portion of the movement of said arm, stationary means cooperable with said link for holding the link in place against said abutment means during a portion of the path of movement of said arm, a crank operated rotary member remote from said crank arm, and a pair of links connecting said rotary member with said arm for imparting turning movements to the latter from rotary movements of the former.

2. A vehicle window regulator comprising a crank arm, means to turn the arm about a horizontal axis, a link connecting the end of the arm to the window, means for establishing a constant angle position between the link and arm during a portion of the path of movement of the arm, means for positively retaining said link against movement relative to said arm out of said constant angle position during a portion of the movement of the latter, a crank operated rotary member remote from said crank arm, and a pair of links connecting said rotary member with said crank arm for imparting turning movements to the latter from rotary movements of the former.

STANLEY W. NICHOLSON.
